AIRSHIP

Original application filed September 6, 1921, Serial No. 498,605. Divided and this application filed March 17, 1931. Serial No. 523,250.

This invention pertains to airships. More particularly, it pertains to airships whose frame, as is usual, is divided into compartments or chambers in which are fabric containers for the lighter-than-air gas. In a preferred form of the invention, the gas container in a compartment of the airship is supplemented by a container which may be of similar construction and aspect but is charged with less expensive lifting gas or with air.

Airships have hitherto been provided with high grade lifting gas as hydrogen or helium in containers but there has been waste of the valuable gas when gas has had to be discharged because of ascent from one elevation to another, as, for example, from ground levels to cruising levels. One of the objects of the present invention is to provide an improved means to avoid such waste.

This is conveniently accomplished, according to the present invention, by providing in each said chamber or compartment of the ship's frame a plurality of gas containers which are external to each other and which together fill the chamber, — an arrangement and construction which herein for brevity will be designated by the single word "complementary." These complementary containers are charged with different kinds of gas, one being charged with the expensive and high grade principal lifting gas, as hydrogen or helium, herein called the main body of lifting gas, and the other being charged with a gas herein called the auxiliary gas, whose value is low, because of its inferior quality, such as spent lifting gas or air. Both of said containers are equipped with means for escape of contents to the atmosphere. Then when the main body of lifting gas tends to expand, due to decreasing density of atmosphere on ascending from ground to cruising levels, the expansion of the containers charged with the valuable lifting gas is permitted, without wastage of contents, because of the complementary containers of auxiliary gas being arranged to yield commensurately. The result is that the latter are vented to the at-

mosphere before wastage of pure lifting gas begins.

It is a particular feature that the complementary containers are external to each other. It follows that the body of poor gas in the auxiliary container is in proximity to the high quality gas only along one side, or perhaps two sides, of its total surface. And on that side or sides the two gases are separated by the two layers of fabric which respectively constitute the container walls, as well as a film of atmospheric air which is between the walls.

It has been found that there is a tendency of air to pass from air into hydrogen or helium, diffusing through the pores of the fabric wall that holds the lifting gas, and this infiltration is a pronounced evil in that it gradually vitiates the expensive gas for lifting purposes. We have discovered a remedy by placing the lifting gas under pressure such that the contained gas tends to pass outward through the pores of the fabric of the container, thus by mechanical action of outrush through microscopic pores pushing back those particles of oxygen or other air gas that would enter by osmosis.

The complementary arrangement of gas containers external to each other permits of the applying of a squeezing pressure to the container of the main lifting gas, by the application of expansive pressure to the auxiliary container, as by pumping more gas into it, so that the contents of these two may be of equal pressure, and both of them greater than the local atmospheric pressure, without the equilibrium of pressure of gas in the auxiliary chamber with pressure of gas in the main chamber giving opportunity for osmosis to proceed from the auxiliary of poor gas or air into the main body of high grade gas.

In the accompanying drawing, forming a part hereof, Figure 1 represents more or less diagrammatically an airship provided with complementary gas containers, as herein described.

Figure 2 represents a cross section through the airship taken transversely with respect to its longitudinal axis; and

Figure 3 shows, on a somewhat larger scale, an alternative arrangement in which a number of connected containers are employed.

5 In the practice of the invention, the containers 21, located within the shell 4 of the airship, are filled with lighter-than-air lifting gas which is of high quality in the sense that, whatever be its kind or quality in an absolute sense, its quality is "high" as the term is used here because it is relatively uncontaminated by infiltration of air. But containers 22 are filled with the more or less spent lifting gas, or with air, or other less 10 expensive and less good gas, as for example any cheaper buoyant gas, which is to be vented to the atmosphere when decrease of atmospheric local pressure requires expansion of the main body of lifting gas.

15 Preferably these containers 21 and 22 are in the form of collapsible gas bags contained within the confining walls of the chamber or other limited space, the bags 21 being exterior to the bags 22. By arranging them 20 in this manner and using a fabric at least a portion of which is collapsible, as indicated in the drawing, container 22 is always complementary to container 21, whatever be 25 their relative stages of expansion or contraction.

As shown in Figure 3, a header 7 with branch pipes 125 having control valves 127 may serve to connect the several main gas bags 21 where more than one such bag is 30 employed for each chamber section of the dirigible. Similarly a header 120 with branch pipes 126 having control valves 128 may connect the several auxiliary containers 22 for air or inferior gas. To this end, 35 and with the aid of apparatus and valves which it is not necessary to illustrate but whose presence is implied from and typified by the respective representations of headers 7 and 120 (which lead from and to suitable 40 apparatus and valves that are not shown), air or gas may be removed from or blown into any one of the bags as desired, or the contents of each system may be permitted 45 interflow, among the bags of its own system.

50 It will be understood that automatic valves may be provided and pumping apparatus automatic or otherwise, either connected with these headers or directly connected with the bags, by which the pressure 55 in both containers can be maintained above that of external air in the locality wherever the ship may happen to be; and moreover these valves may also be so related that, in case of a predetermined too great excess 60 of gas pressure over atmosphere, the auxiliary gas discharge valve shall be set to discharge gas at a lower pressure than does the discharge valve for the main body of 65 lifting gas. This may happen on rise in elevation; on descent the automatic pump-

ing control will operate to introduce more gas into the auxiliary container from atmosphere or from other source of supply, in order to keep the two complementary bags swelled out against atmosphere and at the 70 desired pressure above atmosphere. As these devices are not part of the invention here claimed, and can otherwise be known, they are not illustrated herein.

At the beginning of a flight, the auxiliary 75 bags 22 are filled with an inferior and less expensive gas than that which fills the main gas bags 21. As the airship ascends to its 80 cruising altitude, the atmospheric pressure gradually decreases with the result that the 85 gas in the bags tends to expand and would place its containing wall in excessive tension if not allowed to expand. Gas in the auxiliary bags 22 is then allowed to escape to the atmosphere through appropriate relief valves, which preferably are automatic as above indicated, thus letting the main bags 21 expand by squeezing the auxiliary bags.

This does not interfere with the making of 90 the lifting gas an active element of the invention, for certain qualities which may be varied from time to time in the operation of the ship. In a typical instance, the gas 95 containers of a ship located at a station and about to begin a flight are furnished with gas at a predetermined temperature different from the local atmospheric temperature. Under certain circumstances, this 100 will be at a higher temperature and under others, at a temperature below the local atmospheric temperature, as required. A quantity of such gas is provided and permitted to fill the containers.

The balance 22 of the space within the 105 airship, to be occupied by lifting gas when the main gas containers 21 have expanded fully, is at the moment of ascent occupied by air or by a lifting gas of less valuable 110 quality from the gas used in flight. Such air or less valuable gas is confined in the 115 flexible containers 22, so situated that when the uncontaminated lifting gas attains a pressure to a predetermined degree above that of the surrounding atmosphere, it will cause the inferior gas to escape.

The result is that when the pressure of the atmosphere decreases, as occurs in rising from the ground to a cruising altitude, the expansion of the cruising gas will not 120 result in the discharge of such gas into the atmosphere until all the less valuable gas has first been discharged. By using a pre-heated less-valuable gas for the auxiliary 125 containers during the initial lift, in a container thus fitted, the installation, space and weight of heating machinery for the auxiliary containers is avoided, and an advantage 130 is gained by a saving both of quantity of lifting gas and of quantity of auxiliary gas.

Obviously, improvements and modifications may be made without departing from the inventive thought. Thus any preferred arrangement of containers 21, 22 may be employed, as, for example, providing one large chamber for uncontaminated lifting gas and two or more auxiliary chambers for spent gas or air. The chambers may be arranged as preferred and may, if desired, be heated or cooled. It will be understood, also, that the structure disclosed in the drawing is adapted for other uses than that described, as, for example, for providing a container for fuel gas within the gas chambers of the ship.

The subject matter of this application has been divided out of our co-pending application 498,605, filed September 6, 1921, for "Airships". It is intended that the patent to be based on the present application shall cover, by suitable expression in the appended claims, whatever features of patentable novelty are found in the invention herein disclosed.

We claim:

1. In an airship, an upper gas container for lifting gas and a lower gas container for gas of different properties, the two containers being external to each other, with atmospheric air intervening between them, but having contiguous walls, movable in unison and in harmony with expansion and contraction of gas in the upper container, and means whereby gas flows out from the lower container in harmony with said expansion; the said contiguous walls extending in direction approximately normal to the direction of gravity, whereby mutual abrasion is minimized.

2. In an airship deriving upward lift from lighter-than-air gas, and having two complementary gas containers, each of which is expandible and contractable, these two containers having freely movable contiguous walls; a quantity of lighter-than-air gas in one of said containers, comprising a main body of lifting gas; a quantity of lighter-than-air gas in the other said container, comprising an auxiliary body of lifting gas; an automatic release-to-atmosphere valve for each said container, adapted to hold gas within its container at a pressure above current external air pressure, and to discharge gas from within when the differential of the internal over the external pressure attains a predetermined value;—the co-operating combination of the two said containers, their freely movable said walls and their several said release valves, in which the said release valve of the auxiliary body is organized to open at a lower differential above the current atmospheric pressure than is the said release valve for the main body; whereby a rise of pressure differential of the main body above atmosphere acts through the movable walls

to raise pressure in the auxiliary body and thereby, by releasing gas from the auxiliary body, and by movement of contiguous walls, to expand while being retained in its said main container.

3. In combination, in an airship deriving an upward lift from lighter-than-air cruising gas on board, a first flexible container, partially expanded, filled with said cruising gas; a second flexible container; means to confine the said two containers exteriorly of each other within a space having a less cubic capacity than the sum of the cubic contents of the two said containers measured separately when fully inflated; there being gas releasing means for the auxiliary gas container, operated by increase of differential of pressure of the cruising gas above current local atmospheric pressure; and, in the said second flexible container, a quantity of lighter-than-air auxiliary lifting gas of a different quality from the cruising gas, being gas previously used for cruising purposes, but which, by reason of admixture of other gases with it, has become unsuited for cruising purposes.

Signed at San Bernardino, California, this eleventh day of November, 1930.
